SUCTION CLEANER

Dale C. Gerber, North Canton, Ohio, assignor to
 The Hoover Company, North Canton, Ohio, a
 corporation of Ohio

Application October 18, 1935, Serial No. 45,531

9 Claims. (Cl. 183—51)

This invention relates to improvements in suction cleaners and more particularly to a device to be incorporated in a suction cleaner as a means of indicating the conditions within the bag or dust receptacle as regards the amount of dirt therein and hence as a signal to warn the user that the bag should be emptied.

As well known in the art, the type of dust receptacle more commonly used with suction cleaners is a fabric bag removably attached at the exhaust outlet from the fan, the fabric thereof being permeable in a degree sufficient to eliminate any appreciable resistance to the air discharged into the bag. However, as dirt accumulates in the bag, the permeability of the fabric decreases and the resulting increased resistance to the passage of air therethrough creates a back pressure which is manifested in a decrease in the efficiency of the cleaner.

20 The object of the invention is to provide a simple and compact type of indicator together with a novel mounting therefor, whereby the same is completely housed and protected against damage and yet conveniently located for ready visibility by the operator.

A preferred embodiment of my invention is disclosed in the accompanying drawing in which:

Figure 1 is a view in side elevation of the main casing of a suction cleaner showing the bag pressure indicator incorporated in a ring intermediate the bag and the cleaner proper.

Figure 2 is a view in cross section taken on line 2—2 of Figure 1 showing the mounting of the pressure indicator in the ring.

Figure 3 is a perspective view of the parts of the ring including the indicator as they appear when dis-assembled, and

Figure 4 is a perspective view of the indicator dial.

40 As shown in Figure 1, a typical suction cleaner comprises a wheeled casing 1 having a nozzle portion 2 at its forward end and leading to a fan chamber immediately below the dome-like casing 3 housing the motor for driving the fan. Beyond the fan chamber is an exhaust passage 4 terminating in an abruptly flaring outlet connection 5, to which is removably attached a fabric dust bag 6 of the usual elongated shape and having its upper end preferably supported by 45 the cleaner handle, not shown herein except for one of the arms of the bail 7 by which the handle is pivotally mounted on the casing 1.

During the cleaning operation, the bag 6 is closed to the atmosphere, the permeability of the fabric permitting the air to pass therethrough

while retaining the dirt carried with the air into the bag.

The bag 6 is preferably attached to the outlet connection 5 through the medium of a ring 8, having flush contact with the outlet connection 5, and provided with diametrically opposed notched ears 8^a, 8^a adapted to engage a pair of complementary bolts 5^a, 5^a mounted at the edge of the outlet connection. The ring has flush contact with the outlet connection at one edge and 10 at its opposite edge is provided with an annular flange 8^b to which the inlet end of the bag proper is secured by means of a clamping ring 6^a.

As clearly shown in Figures 2 and 3, the ring 8 is made up of two sections, namely, the main 15 casting or body and an arcuate segment 9, forming the upper section of the complete ring and bearing on a flat seat 10 tangential to an eccentric opening through the main body of the ring. At the central portion of the seat 10 is a circular opening 11 surrounded by a shallow substantially semi-circular recess 10^a and immediately below the circular opening 11 is a U-shaped wall segment 12 depending into the annular opening through the ring and forming a rectangular frame 20 adapted to partially enclose a portion of the indicator as will presently be seen.

25 The segment 9 of the ring 8 consists of a wall section curved transversely through to a 90° angle and having a rounded top edge meeting its flat bottom edge to form sockets 9^a, 9^a for screws 13, 30 13 whereby the segment is anchored to its seat 10 as clearly shown in Figure 2. Moreover, the segment has a centrally disposed chamber included between a pair of upright webs 9^b, 9^b and in the wall of the segment between the upright webs is a rectangular opening or window 9^c, 35 facing upwardly and rearwardly toward the operator of the cleaner and therefore visible from operating position.

40 Now, seating in the opening 11 with portions extending above and below is the indicator 14 comprising a circular base plate 15 having a marginal flange 15^a supporting the bellows member 16. Extending axially of the base plate 15 45 and depending into the bellows member 16 and attached at its lower end to the end wall thereof, is a pin 17 with its upper end projecting through and a short distance above the plate 15 and contacting with the underside of an indicator dial 18, 50 pivotally supported on the base plate. The dial 18 is a member of thin metal shaped to form an arcuate dial face 18^a including an angle of about 60° and having at one end a pair of radially extending arms 18^b and at its opposite or lower 55

end an in-turned curved finger 18^c, extending generally toward the ends of the arms 18^b, all as clearly shown in Figure 4. The dial member is pivotally mounted on a pin 19 supported between two upstanding lugs 15^b, 15^b on the upper side of the base plate 15 and passing through holes in the ends of the radial arms 18^b of the dial member. And finally, a coil spring 20 surrounds the pin 19 with its free end portion bearing downwardly upon the end of the finger 18^c of the dial member, thereby acting to hold the moving parts of the indicator in their normal or depressed position as shown in Figure 1.

In assembling the indicator in the ring, the dial 18 is positioned to swing in an arc concentric with the wall of the chamber in which it is located and opposite the window 9^c therein and through which may be seen the words "Clean", "Caution" and "Dirty", the latter being placed at the lower end of the dial plate and preferably on a background of red or other visible color (Figure 4).

When the cleaner is not in operation, it is apparent that the pressure indicator will assume its normal position, namely, with the bellows member 16 extended and the indicator in its depressed position, in which the word "Clean" is visible through the window. Moreover, the indicator will continue to register "Clean", while the machine is in operation and so long as the bag 6 is relatively clean. However, as the bag becomes dirty the increasing back pressure causes the bellows member to collapse, and the pin 17 rotates the dial member, first, to a position in which the word "Caution" registers through the window opening signifying that the bag is approaching a dirty condition, and lastly, to a position in which the word "Dirty" appears, thus warning the user that the bag should be emptied without delay.

Considering the novel features herein disclosed, it is to be observed that the invention resides not so much in the indicator per se as in the adaptation of the ring 8 as the support and housing for the indicator. As shown, this ring is an integral part of the bag 6, in that it is permanently attached thereto and is removed therewith when the bag is emptied of its dirt contents, it being done by loosening the nuts 5^b, 5^b and releasing the ears 8^a, 8^a from the bolts 5^a, 5^a.

Now, it is common practice to removably attach a dust bag to the outlet connection of a cleaner by means of a plain ring having the same type of connection as herein shown. But manifestly the ordinary bag-ring so called, would not provide a mounting for an indicator, without completely redesigning both the ring and the outlet connection from the cleaner.

In the first place, the ring has to be widened considerably to accommodate the indicator. Secondly, in order to provide a chamber for the indicator in the upper portion of the ring it is necessary to resort to the eccentric inner and outer surfaces unless the dial member be enclosed within a casing projecting from the surface of the ring. However, it is possible to include the indicator within the circumference of a ring by enlarging its external diameter slightly, retaining its internal diameter to the required exhaust opening, but offsetting the axis thereof, and finally, by redesigning the outlet connection from the cleaner casing 1 to conform to the ring.

Thus, as shown in Figure 1, the outlet connection 5 not only has the same diameter as the ring 8, but at the base of the upwardly and outwardly flared portion thereof is a U-shaped web

21 extending transversely across the mouth of the opening with its outer edge flush therewith. Thus, when the ring 8 is attached this web 21 registers with the outer edge of the U-shaped frame 12 surrounding the bellows of the indicator, thus closing off the chamber in which the indicator is located from the air passage below and through which the dust-laden air is impelled with great force into the bag.

In this manner the indicator is protected from 10 direct contact with the exhaust dirt and yet the bellows is subjected to the pressure in the bag through the open side of the frame 12 facing toward the inlet thereto.

From the foregoing discussion it is manifest 15 that although the ring 8 is designed as a mounting for the indicator and as an integral part of the bag, it need not necessarily be a part of the bag or removable with it in the act of emptying its contents. In other words, it may be considered 20 as a separate unit or adapter to be inserted between the cleaner proper and its bag when it is desired to include a pressure actuated signal device as a part of a complete cleaner. In short, 25 it is not essential that the annular member forming the indicator mounting be limited to a bag ring or a part of the bag or for that matter, to any of the structural details herein disclosed except in so far as the invention is set forth in the appended claims.

I claim:

1. In a suction cleaner, the combination of a suction producing unit having an outlet connection including a ring divided longitudinally to provide a rearwardly opening chamber and an 35 exhaust passage, an air pressure indicator mounted in said chamber and a dust receptacle attached to said ring and communicating with said chamber.

2. In a suction cleaner, the combination of a 40 suction producing unit having an exhaust passage terminating in a ring divided longitudinally to provide a chamber therein, a dust receptacle attached to said ring and communicating with said exhaust passage and said chamber, and 45 an air pressure indicator mounted in said chamber.

3. In a suction cleaner, the combination of a suction unit having an exhaust passage terminating in a ring having a radially offset chamber separated from said exhaust passage by a longitudinally extending partition wall and provided with a rearwardly facing opening, an air pressure indicator mounted in said chamber and a dust receptacle attached to said ring and communicating with said exhaust passage and the opening to said chamber.

4. In a suction cleaner, the combination of a suction producing unit having an exhaust passage terminating in an outlet connection including a ring having a rearwardly opening chamber separated from said exhaust passage by a longitudinally extending partition wall, a pressure indicator comprising a pressure responsive element subject to the pressure in said chamber and a 60 dust receptacle attached to said outlet connection and communicating with said exhaust passage and said chamber.

5. In a suction cleaner, the combination of a 70 suction producing unit having an exhaust passage terminating in a bag supporting ring divided transversely to form a chamber adjacent said exhaust passage and having a rearwardly facing opening, a pressure indicating device having a bellows housed within said chamber and a 75

dust bag attached to said outlet connection and communicating with said exhaust passage and the rearwardly facing opening to said chamber.

6. In a suction cleaner, the combination of suction producing unit having an exhaust passage terminating in a ring divided by a transverse partition wall to form a rearwardly opening chamber offset from said exhaust passage, a pressure indicating device mounted in said chamber and having a bellows, a U shaped wall segment partially enclosing said bellows and forming the opening to said chamber and a dust receptacle attached to said outlet connection and communicating with said exhaust passage and said chamber.

7. In a suction cleaner, the combination of a suction producing unit having an exhaust outlet, an annular member adapted for detachable connection with said outlet and having a partition wall dividing the same into a passage forming an extension of said exhaust outlet and a chamber having a rearwardly facing opening, a pressure indicator mounted in said chamber and a dust bag connected to said annular member and communicating with said passage and said chamber.

8. In a suction cleaner, the combination of a suction producing unit having an outlet connection, an annular member adapted for detachable connection to said outlet connection and having

a passage forming an extension of said exhaust outlet and a chamber separated from said passage by a partition wall extending longitudinally of said member and providing a rearwardly facing opening from said chamber, a pressure indicator housed in said chamber and having a bellows seating in said partition wall, a U shaped wall segment integral with said partition wall and enclosing the space around said bellows and a dust bag detachably connected about the outer edge of said annular member and including said exhaust passage and the opening to said chamber.

9. In a suction cleaner, the combination of a suction producing unit having an outlet connection, an annular member adapted for detachable connection to said outlet connection and having a passage forming an extension of said exhaust outlet and a chamber separated from said passage by a partition wall, a pressure indicator mounted in said chamber and having a bellows seating in said partition wall, a U shaped wall segment integral with said partition wall and enclosing the space around said bellows and forming a rearwardly facing opening to said chamber and a dust bag detachably connected to the outer edge of said annular member, with its entrance including the outlet from said exhaust passage and the opening to said chamber.
